UNITED STATES PATENT OFFICE.

LEWIS D. YOUNG, OF PROVIDENCE, RHODE ISLAND, ASSIGNOR TO YOUNG BROTHERS,
OF PROVIDENCE, RHODE ISLAND.

BOX.

Application filed July 24, 1924. Serial No. 727,916.

To all whom it may concern:

Be it known that I, LEWIS D. YOUNG, a citizen of the United States, residing at Providence, in the county of Providence and 5 State of Rhode Island, have invented new and useful Improvements in Boxes, of which the following is a specification.

This invention relates to certain new and useful improvements in boxes and pertains 10 more especially to boxes of the type used for containing and displaying various articles, such as jewelry, cologne bottles, etc.

The primary object of the invention is to provide a box of this type in which the 15 body is composed of a supporting base and an independently formed inner or tray member, the bottom of the latter also forming the bottom of the body and being connected thereto so as to constitute a practically one-piece structure.

A further object of the invention is to provide a tray which projects upwardly from the base and cooperates therewith to form holding flanges and a seat for the 25 cover so as to effectively retain and support the cover in closed position.

The invention still further aims to provide novel means for hingedly connecting the cover to the body and has other and 30 further objects which will be later set forth and manifested in the course of the following description.

In the drawings:

Figure 1, is a perspective view of the 35 invention, the cover of the box being closed;

Figure 2, is a section on line 2—2 of Figure 1, and

Figure 3, is a section on line 3—3 of Figure 1.

In proceeding in accordance with the present invention, an open base is provided which includes sides 1 and ends 2, the corners of which are extended downwardly to form substantially L-shaped supporting feet 45

3. A tray having a bottom 4, sides 5 and ends 6 is inserted in the open base and is fixedly secured thereto in any suitable manner, such as for instance by gluing. The

bottom 4 of the base is disposed to lie flush with the bottom edges of the sides 1 and ends 2 thereof and to have its sides 5 and ends 6 engage with and against the inner faces of the sides 1 and ends 2 respectively, of the base. The tray sides and ends are of such 55 width so that the upper sides thereof will

project upwardly above the sides and ends of the base so as to form cover engaging flanges.

The cover 8 has sides and ends 9 and 10 respectively for engagement over the projecting or flange-forming portions of the tray and is formed to seat on the upper edges of the sides and ends of the base. A cloth strip is employed to hingedly connect the cover to the body, the upper sides 11 of the strip being glued to the rear side of the cover, while the lower side 11^a of the strip is glued between the rear side of the tray and the rear side of the open base. Finishing material 12, which may be of paper, is glued to the rear sides of the back and cover and conceals the hinging cloth strip 11 from one side thereof, while a piece of sateen or other material 13 is glued to the inner face of the rear side of the tray and to the top of the cover so as to conceal the opposite side of the hinging cloth strip. The cover and body interior may be provided with a padded facing (not shown) if desired.

Having thus described my invention, what I claim as new and desire to secure by Letters Patent is:—

1. In a box, a body including an open base having sides and ends the corners of which are extended downwardly to form supporting feet of approximately L-shape, a tray having a bottom, sides and ends arranged in the base and with its bottom substantially flush with the lower edges of the sides and ends of the base so as to form a bottom for the latter, the upper parts of the tray sides and ends extending above the base sides and ends to form cover engaging flanges, a cover, a flexible hinge strip secured at one side to the outer face of the rear side of the cover and at its opposite side between the rear sides of the tray and base, and finishing strips secured to the body and cover and extending on opposite sides of the hinge strip to conceal the latter.

2. In a box, a body including an open base, a tray fitted in the base and having a bottom forming the bottom of the base and thereby of the body, the upper parts of tray extending above the base to form cover engaging flanges, a cover and a flexible hinge strip secured at one side to the cover and at its opposite side between the tray and base.

3. In a box, a body including an open

base, a tray fitted in the base and having tray and base, and finishing strips secured a bottom forming the bottom of the base to the tray and cover and to the base and and thereby of the body, the upper parts cover and disposed on opposite sides of 10 of the tray extending above the base to the hinge strip to conceal the latter. 5 form cover-engaging flanges, a cover, a flexible hinge strip secured at one side to the In testimony whereof I have signed my name to this specification. LEWIS D. YOUNG.
